(57) **CLAIM**

The ornamental design for a juice board, as shown and described.

DESCRIPTION

FIG. 1 is a top perspective view of the juice board showing my new design;

FIG. 2 is a bottom perspective view thereof;

FIG. 3 is a bottom plan view thereof;

FIG. 4 is a right side elevational view thereof; and,

FIG. 5 is a rear elevational view thereof.

The juice board of the present invention is symmetrical so that the front and rear views are identical as are both side views.
